UNITED STATES PATENT OFFICE.

JOHN VODICKA AND ARTHUR W. KIMBELL, OF CHICAGO, ILLINOIS, ASSIGNEES TO CINCH FASTENER CORPORATION, OF CHICAGO, ILLINOIS, A CORPORATION OF ILLINOIS.

CURTAIN FASTENER.

Application filed April 23, 1920. Serial No. 375,960.

To all whom it may concern:

Be it known that we, JOHN VODICKA and ARTHUR W. KIMBELL, citizens of the United States, residing at Chicago, in the county of Cook and State of Illinois, have invented certain new and useful Improvements in Curtain Fasteners, of which the following is a specification.

Our invention relates more particularly to curtain fasteners designed for use in connection with automobile curtains, though it will be obvious from the following description that it is applicable to a variety of other uses, where a ring such as a grommet is to be removably held upon a stud. The nature of the invention will be understood from the following description in connection with the drawings forming a part of this application and the scope of the invention will be defined in the following claims in which we have endeavored to distinguish it from the prior art so far as known to us without relinquishing part, or abandoning any portion or feature thereof.

In the drawing Fig. 1 is a perspective view showing our improved fastener with the curtain and upright with which it is to be used; Fig. 2 is a view of the inside of the curtain showing the curtain member of the device in perspective from the rear; Fig. 3 is a perspective of a portion of one of the uprights with a post which forms one of the elements of our improved fastener attached thereto; Fig. 4 is an axial section through the curtain member of our fastener, showing the post in locked position therein in dotted lines; Fig. 5 is a perspective of the post element; Figs. 6, 7 and 8 are perspective views of parts of the curtain member of the fastener; Fig. 9 is a section on the line 9, 9 of Fig. 4, looking in the direction of the arrows, showing the parts in the position which they occupy when the fastener elements are in interlocking position; Fig. 10 is a similar view with parts in position which they occupy when the curtain member is being removed from the head of the post; and Fig. 11 represents a section of one of the curtain member elements in perspective.

The post member of our curtain fastener, which, as above stated, is to be mounted upon an upright of an automobile top or in any other suitable position, is formed

with the body portion 13, the screw shank 14^a, to be driven into the frame work of the automobile top, a tapered head 14 and a reduced neck 15 intermediate said head and body as will be presently seen. The curtain member comprises a housing, containing a spring collar or gripping member and adapted to receive the head and a portion of the top of the post. The housing is formed in two sections, an inner section 16 and an outer section 17, each of which sections comprises a broad annular flange 16^a, 17^a and a concentric hollow boss 18, 19 of substantially equal interior diameter, adapted to receive the head of the post. The boss 18 extends inward through the body of the curtain and boss 19 outward, both bosses being open at their respective ends, and the edges of the openings slightly inturned as at 18^a, 19^a for a purpose which will appear. The flange 17^a is formed with a skirt 20 at its periphery and the skirt is formed with a series of tongues 21, which, in assembling the curtain member are projected through corresponding slots 22, in the flange 16^a (see Fig. 6) and also through corresponding slots in a washer or keeper 23, surrounding boss 18 on the inside of the curtain. The tongues are bent over as at 24 upon the washer 23, thus holding the sections 16, 17 and washer 23 together. The section 17 is also provided on its periphery with a series of tongues or lugs 25, arranged respectively intermediate the tongues 21, which lugs 25 extend through openings 26 in flange 16^a and into the curtain but not through the washer or keeper. These lugs may be bent over the flange 16^a as shown in Fig. 4 to hold the parts in position.

The skirt 20, forms a shallow chamber 27, concentric and communicating with the chamber formed by the bosses, and chamber 27 contains a spring collar or gripping member 28 of the form best shown in Fig. 7. Said collar or gripping member comprises an outer peripheral spring 29 and a pair of gripping jaws 30, 31, the spring member and jaws being integral and the jaws being respectively connected to the spring member at opposite ends thereof. Thus the jaws of the gripping member are normally maintained in closed position by the annular spring. As seen in Fig. 7, the

jaws are cut out to form when in contact a substantially circular opening 31, which is slightly larger in diameter than the neck of the post, but smaller than the head of the latter. The chamber 27 containing this gripping member is of sufficient diameter to allow a slight expansion of the latter. It will be noted from an inspection of Figs. 4 and 5 that the head of the post is somewhat tapered as at 33, the extreme end thereof being of a diameter to enter the opening in the gripping jaws when the latter are closed. When the curtain member of the fastener is forced down upon the post, the latter spreads the jaws by wedging action and the jaws pass over the head to the neck where they close and thus secure the annular or curtain member to the post.

To release the curtain member from the post it is of course necessary to spread the jaws of the gripping member and for this purpose the thumb piece or thimble 34 is reciprocably mounted in the boss 19, and formed with diametrically opposite wedge 25 projections or lugs 35, the ends of which extend into recesses or notches 36 in the jaws, each notch being formed partially in one jaw and partially in the other. The thumb piece is hollow to receive the tapered 30 end of the post and enlarged in diameter at its inner periphery, forming the shoulder 37 which coacts with the inturned edge 19^a to limit the outward movement of the thumb piece. Obviously when the thumb piece is 35 pressed inwardly the lugs 35 thereon wedge the spring jaws apart and permit the head of the post to pass therethrough.

We claim:

1. In a curtain fastener and in combination with a post having a reduced neck and a head, a housing adapted to be connected to the curtain and having an opening to receive the post, spring jaws within the housing adapted to encircle the post about 45 its neck, and a reciprocable thumb-piece coaxial with the opening and having means for spreading the jaws slidable in said housing.

2. In a curtain fastener and in combination with a post having a head and a reduced neck, a curtain member comprising a housing having an opening adapted to receive the head of the post, a pair of spring-pressed jaws within the housing adapted to encircle the neck of the post, and a hollow 55 thumb-piece coaxial with the opening and having wedge-shaped lugs projecting between said jaws and adapted to spread the same.

3. In a curtain fastener and in combination with a post having a reduced neck, a curtain member comprising a housing adapted to be secured to a curtain and having an elongated chamber to receive the post, a pair of spring-pressed jaws adapted 60 to engage the neck of the post, a hollow thumb-piece reciprocable within said elongated chamber, and a wedge on the thumb-piece extending between the jaws and adapted to force them apart.

4. In a curtain fastener and in combination with a post having a reduced neck, a sectional housing, a hollow boss on one of the housing sections open at both ends and adapted to receive the head of the post, a 75 hollow thumb-piece mounted to slide in said boss and projecting beyond the same, a pair of jaws within the housing adapted to engage the neck of the post, lugs on said thumb-piece extending between and adapted 80 to spread said jaws when the thumb-piece is depressed.

5. In a curtain fastener and in combination with a post having a reduced neck, a curtain member comprising a section 16 having a hollow boss 18 and a flange 16^a, a second section 17 having a boss 19 and a flange 17^a, a pair of flat spring-pressed jaws arranged between said sections and adapted to engage the post, and an axially 90 movable thumb-piece having wedge-shaped lugs extending between said jaws and adapted when the thumb-piece is depressed to separate the latter.

JOHN VODICKA.
ARTHUR W. KIMBELL.
